UNITED STATES PATENT OFFICE

LOUIS HOFFMAN, OF SAN FRANCISCO, CALIFORNIA

PANEL CONSTRUCTION

Application filed June 18, 1928. Serial No. 286,330.

My invention relates to improvements in the construction of paneling, wainscoting or similar fixtures built of tile, wood, marble, plate glass mirrors, or like material, and it consists in the constructions, combinations and arrangements hereinafter described and claimed.

An object of my invention is to eliminate the present waste of labor and material in the construction, assembling and installation of the above mentioned devices. The present practice of constructing and setting up of wood paneling and wainscoting is to make each part thereof a permanent part of the whole. To do this properly, each part must be made to an exact size and finish. This is necessary in order that parts may be properly assembled and set up. This method requires extreme exactness in the construction and setting up of the different parts.

The present practice of constructing and setting up of vitrolite, marble, plate glass or plate glass mirror, paneling or wainscoting, also requires an exactness in size and finish. Also, in order to install and set up these pieces, it is necessary to drill screw holes in each of the narrow finishing strips. This is necessary because the fixtures are secured to the supporting surfaces by screws or bolts. This drilling of holes weakens the finishing strips and causes some of them to break or crack during the time they are being installed and some at any time subsequent to installation. Also, the pressure of applying the screw directly to the material used, instead of on the brackets as in my invention, causes much breakage and waste of material and time. If the parts of the paneling or wainscoting are cemented to the supporting surfaces, the same exactness in finish and skill is required, but they cannot be removed without the breaking, cracking or scratching of the parts removed. With my invention the various pieces do not have to be built with any exactness. The fixtures will not require persons of any skill to assemble or install them. The danger of cracking, scratching or breaking will be eliminated, and the time required for constructing, assembling or installing will be greatly reduced. The fixtures may be re-

moved and installed elsewhere without in any manner injuring it, and at a cost far lower than that which would be necessary with present methods of construction.

It should be remembered that the device in no case becomes a part of the property to which it is attached, but always remains a fixture which can be readily removed.

Panels, pilasters, rails and bases of standard sizes, all trimmed and polished on one face and two edges, will be carried in stock ready for installation, for any size place. Under the present method, it is necessary to fit each piece on the job, causing refinishing of the parts altered, but with my invention all refitting and refinishing is eliminated. Any fitting or cutting necessary to accommodate any certain area of wall will be done to the under frame that supports the vitrolite or other finishing materials. All necessary fastening to any surface will be done on the wood underframes. All alterations on the finished pieces carried in stock will be done on the two unfinished edges, and these unfinished edges will be covered by brackets, and thus present a secure and finished job without exact fitting and refinishing as is now required.

Other objects and advantages will appear as the specification proceeds, and the novel features will be particularly pointed out in the appended claims.

My invention is illustrated in the accompanying drawing forming a part of this application, in which

Figure 1 is a front elevation of the device shown in operative position, a portion being broken away for disclosing the hidden supporting structure;

Figure 2 is a section along the line 2—2 of Figure 1;

Figure 3 is a perspective view of one of the supporting brackets looking at the device from the rear; and

Figure 4 shows a perspective view of a different bracket looking at it from the front.

The device is installed directly in front of a wall or partition. I mount a channel iron 4 beneath the device, and this is supported by the floor 5. This iron may be up

against the rail 3 if desired, or it may be spaced slightly therefrom by the layer of plaster 6 as shown in the drawing.

At the top of my panel construction, I 5 mount an angle iron 7, this being secured to the wall by screws 8 or other suitable fastening means. In the channel iron 4 and the angle iron 7, I mount frames indicated generally at 9, these frames varying in size according to the type of panel construction I 10 intend to use.

Reference to Figure 1 shows large panels A and small panels B. I will therefore provide large and small frames, and these 15 frames will abut each other along their vertical edges 10 as shown at the left hand lower corner of Figure 1.

Each frame has a rabbet 11 that extends around the four sides for receiving the panel sections A and B. The sections may be of any material desired, and in order to have a contrast, I make the panels A and B of white vitrolite, while the strips holding them in place are of black vitrolite.

25 The strips 12 overlie the frames 9 and lap over the edges of the panels A and B. The strips are secured in place by brackets or binders indicated generally at 13 (see the enlarged views of the binders in Figures 3 and 4). The binders not only secure the strips in place, but also act as ornaments. In Figure 4 I show the type of binder or bracket that is disposed at the top of the device. Figure 3 shows the bracket used midway between the top and bottom. The brackets at the bottom are longer than the others in order to receive the relatively wide base strip.

40 The brackets have legs 14 (see Figure 3) that bear against the panels A and B, and these legs define recesses 15 that are large enough to receive the strips 12. Openings 16 are provided in the brackets, through which screws 17 are passed (see Figure 2), these screws passing on into the frames 9 for 45 securely holding the brackets in place. The legs of the bracket are not quite as long as the thickness of the strips 12. This is to assure a clamping action of the bracket upon the strips when the former are screwed into place. 50 This type of construction also permits slight variations in the thicknesses of the various parts, and the brackets will still securely clamp the panels and strips in place.

In dismantling the device, all that is necessary is to remove the screw 17, whereupon 55 the strips 12 and panels A and B may be removed. The frames 9 may now be taken down, and likewise the channel iron 4 and the angle iron 7. The device may be quickly 60 secured to any other supporting surface, and will closely resemble a permanent structure when in position. The ends of the strips 12 enter the recesses 15, and in the case of the vertically-disposed strips, the lower ends rest 65 upon the screws 17 and are thus supported.

Although I have shown and described one embodiment of my invention, it is to be understood that the same is susceptible of various changes, and I reserve the right to employ such changes as may come within the 70 scope of the appended claims.

I claim:

1. The combination with a supporting surface, of a plurality of frames removably secured to said surface, each frame having a recessed portion for receiving a panel, panels carried by each frame and being receivable in the recesses, strips covering the adjacent edges of said panels, and brackets covering the ends of said strips, said brackets being secured to said frames by screws. 75

2. The combination with a supporting surface, of a panel construction removably secured thereto and comprising frames removably secured to said surface and having recesses therein, panels removably disposed in said recesses, strips covering the adjacent edges of the panels, brackets having legs straddling the ends of the strips and stopping short of contacting with the panels, and means for removably securing the brackets to the frames. 85

3. A removable panel construction comprising a plurality of frames having panel receiving recesses, panels received in said recesses, strips covering adjacent edges of the panels, brackets, and removable means for securing the brackets, strips and panels to the frames. 95

4. A removable panel construction for a surface comprising frames removably secured to the surface adjacent to the marginal edges of the frame, panels removably carried by the frames, strips for holding the panels to the frames and for covering the adjacent edges of the panels, brackets for holding the strips in place, and means for removably securing the brackets to the frames, whereby the strips and panels are also removably secured to the frames. 100
